APPAREL BELT

Filed April 8, 1947

UNITED STATES PATENT OFFICE

2,499,717

APPAREL BELT

George Noel Bolinger, Shelbyville, Ill.

Application April 8, 1947, Serial No. 740,039

1 Claim. (Cl. 2—321)

1

The present invention relates generally to the apparel art and is more particularly directed to an improved belt of the type adapted to be worn about the waist for the purpose of supporting or restraining articles of clothing of the wearer or for ornamentation effect.

The principal object of the invention is to provide a belt formed of a plurality of strands of helically wound strip material, the width of the various convolutions of the coils relative to the maximum width of the spaces therebetween as determined by the degree of elasticity of the coils being such that the individual coils will not become interlocked under normal usage, thereby obviating the employment of additional spacer elements or other connecting means between the strands.

Another object of the invention is to provide a belt of the general type described formed substantially entirely of a synthetic plastic material, thereby permitting a practically unlimited choice of colors or color combinations and at the same time effecting a slenderizing appearance and comfortable, snug fit on the wearer.

A further object of the invention is to provide a plastic belt of the type described having a buckle of simple and rugged construction formed of a similar plastic material which may be inexpensively and rapidly produced and which also partakes of the color selective nature of the belt proper.

An additional object of the invention is to provide a buckle for a belt of the type described wherein the belt gripping portions of the buckle elements extend at a slight angle relative to the interengaging portions thereof in order to more nearly conform to the body of the wearer when engaged.

Other objects and advantages of the invention will become apparent during the course of the following description.

In the drawings I have shown one embodiment of the invention. In this showing

Fig. 1 is a over-all perspective view of a preferred form of belt in accordance with the present invention;

Figs. 2 and 3 are fragmentary front elevational views to an enlarged scale of a segment of the belt of Fig. 1 illustrating the coils of the strands thereof in closed and maximum open position, respectively; and

Fig. 4 is a detailed perspective view of the buckle illustrated in Fig. 1.

Referring now in more detail to the drawings, there is illustrated in Fig. 1 a belt comprising a

plurality of substantially parallel strands 10, 12, 14, 16 and 18 lying relatively close together and joined at their free ends by mating buckle elements 20 and 22, respectively, forming a broad band adapted to encircle the trunk or waist portion of the body of the wearer. Each of the strands 10—18 is preferably formed from a relatively flat narrow strip of a suitable synthetic plastic material, preferably of the thermosetting type, which has been wound in a helical fashion about a mandrel or the like to form a flexible hollow tube. As illustrated in Figs. 1 and 2, the edges of the adjacent convolutions within each strand are in contact or approximately so after the winding operation and have the general configuration illustrated in these views at such times as no tension exists within the belt. Although I have referred to the strands 10—18 as being formed from a relatively flat strip of material, it is also contemplated that the strips may be slightly convex along one or more surfaces and as illustrated in Figs. 1 and 2, it will be noted that each convolution is actually provided with a slightly convex outer periphery, as indicated by reference numeral 24.

As indicated above in the statement of the general objects of the invention, a most important feature of my improved belt resides in the fact that I have substantially eliminated the necessity of providing auxiliary spacer elements or other interconnecting structure located at a point remote from the belt buckle. This result is accomplished chiefly by employing a material having such qualities of elasticity and resilience as compared with the width of the coils that a single convolution of one strand cannot become accidentally interlocked or engaged between a pair of adjacent coils of another strand. Thus by reference to Fig. 3 wherein the strands 10—18 are shown in the maximum stretched position which they will occupy under any reasonable conditions of normal usage, it will be noted that the width of the strip material in a single coil 26, as designated by the dimension x , is considerably larger than the space 28 between the edges 30 and 32 of any two adjacent coils, as indicated by dimension y , so that no individual coil 26 can be forced into a space 28 without exceeding the elastic limits of the belt material.

Referring now particularly to Figs. 1 and 4, there is illustrated a preferred form of buckle which may be employed in conjunction with the flexible strands 10—18 for securing my improved belt in operative position about the body of the wearer. As shown in these views, the buckle ele-

ments 20 and 22 are seen to comprise generally flat, rectangular members 34 and 36 provided with mating undercut surfaces 38 and 40, respectively. The buckle element 22 is provided at its undercut portion 40 with an elongated aperture 42 therein. An elongated angle shaped hook 44 projects from the undercut surface 38 of the buckle element 20 and is adapted to be releasably engaged within the aperture 42 when the belt is in operative position. Each of the buckle elements 20 and 22 is also provided with belt gripping means in the form of a plurality of evenly spaced parallel cylindrical fingers 46, 48, 50, 52 and 54 and 56, 58, 60, 62 and 64, respectively, which extend laterally from the flat portions 34 and 36 at a slight angle relative to the latter. The fingers 46—54 and 56—64 are received within the respectively opposite open ends 66—74 and 76—84 of the strands 10—18 and are adapted to be firmly secured therein as by means of a suitable adhesive, or the like. It is to be particularly noted that the slight angle between the fingers 46—54 and the member 34, as well as that between the fingers 56—64 and the member 36, in each case opens inwardly or toward the body of the wearer when the belt is in operative position so as to conform more nearly to the natural body contours.

It will also be particularly noted in Figs. 1 and 4 that the exposed outer surfaces of the members 34 and 36 are provided with a plurality of longitudinally extending grooves 86 and 88, respectively, to provide a plurality of convex ridges 90 and 92 equal in number to the number of strands 10—18. Thus, as will be noted in Fig. 1, when the opposite ends of the belt are engaged by insertion of the hook 44 within the aperture 42, the exterior of the buckle has the general appearance of forming continuations of the various strands 10—18 which thereby simulate substantially continuous closed loops and provide a most desirable, neat appearance.

Although I have illustrated herein a belt having five separate strands, it will be obvious that any suitable number of such strands may be employed in accordance with the wishes of the manufacturer or retailer. Also, while I have designated a thermosetting plastic material as a preferred material of construction in view of its multiple advantages such as economy, ease of manufacture, and wide selection of colors and

color combinations, it will be obvious that other materials possessing the requisite qualities of elasticity and resilience may be employed without departing from the spirit of the invention.

While I have described in the foregoing only a single preferred embodiment of this invention in detail, it is to be understood that numerous changes can be made in size, materials, and arrangement of parts without departing from the principles of the invention as set forth in the appended claim.

I claim:

A belt comprising a plurality of substantially parallel strands lying relatively close together to form a broad band adapted to encircle the body of the wearer, each of said strands being formed of relatively flat narrow strip material helically wound to form a hollow tube, the edges of adjacent convolutions of each strand being approximately in contact when the strand is in unstressed condition and the strand possessing a substantial degree of endwise elasticity whereby it is capable of being substantially elongated within the elastic limits of the material, the width of the strip being wider than the spaces between adjacent convolutions of the strand when the latter is stretched substantially to its elastic limit to prevent interlocking of adjacent convolutions of the strip, and a buckle comprising a pair of engaging members, each of said members having projecting rigid parallel fingers inserted in and secured to the ends of the strands, the strands being wholly free of each other between their ends to be held in approximately parallel relationship solely by the stretching of the strands around the body of the wearer.

GEORGE NOEL BOLINGER.
